UNITED STATES PATENT OFFICE

CLAUDE P. MCNEIL, OF WHITING, INDIANA, ASSIGNOR TO STANDARD OIL COMPANY (INDIANA), OF CHICAGO, ILLINOIS, A CORPORATION OF INDIANA

RECEPACLE FILLING APPARATUS

Application filed March 31, 1930. Serial No. 440,216.

This invention relates to apparatus for filling receptacles with liquids or fluent material and pertains more particularly to an apparatus for filling barrels with asphalt.

5 Asphalt may be taken as an example of a viscous sticky mass which is ordinarily hard to handle. The object of my invention is to provide a means for handling this material expeditiously and for filling a maximum 10 number of receptacles in a minimum amount of time, to provide an apparatus which can be easily operated and controlled from a single point, and to provide an apparatus which is simple, rugged, inexpensive and 15 efficient.

The invention contemplates a traveling carriage carrying a movable feed discharge device which is connected to a flexible feed supply and on which is mounted a novel 20 system for regulating the position of the carrier and the flow of asphalt through the feed discharge nozzles. The invention will be more fully understood from the full detailed description of a preferred embodiment.

25 In the accompanying drawings wherein similar parts are designated by like reference characters throughout the several views:

30 Figure 1 is an elevation of my improved apparatus;

Figure 2 is a plan view thereof or more precisely speaking is a horizontal section taken along the lines 2-2 of Fig. 1;

35 Figure 3 is a vertical detailed section of the carriage taken along the lines 3-3 of Fig. 1;

40 Figure 4 is a detailed end view of the nozzle taken along the lines 4-4 of Fig. 1; and

Figure 5 is a vertical section taken along the lines 5-5 of Fig. 1.

Referring to Fig. 1, vertical columns 10, which are supported by concrete bases 11, 45 carry horizontal beams 12 which are held

rigid by suitable braces 13. Arms 14, which are supported by I-beams 15, carry channel beams 16 on which are mounted rails 17.

A movable carriage is mounted to travel backwards and forwards on rails 17. This 50 carriage is shown as a single I-beam 17 carrying at each end yokes 19 in which are journaled shafts 20. Wheels 21 are keyed on these shafts and are held in position on rails 17 by yokes 19, suitable spacers 22 being used as washers to properly position or align the wheels. Pulleys 23 are also keyed to shafts 20 so that the carriage may be driven in the manner hereinafter described.

The I-beam 18 carries depending supports 24 which are braced by angle bars 25 and which carry the movable feed discharge apparatus. (See Figs. 1, 5, and 3.)

Supports 24 carry large pipe 26 to which is secured outstanding brackets 27. These 65 brackets carry journal plates 28 which are reinforced by brackets 29. A plurality of horizontal rods 30, 31, and 33 are journaled in plates 28. One end of each of these rods is secured to a crank-arm 34. The free end 70 of each crank-arm 34 is pivoted to link 35 which actuates a lever 36 for controlling the opening in valve 37 and thereby controls the flow of fluent material through discharge pipe 38.

75 This discharge pipe or nozzle is connected to an inner pipe 39 which is supplied with fluent material by a flexible feed system. The feed system includes a vertical pipe 40, an elbow 41 which is horizontally rotatable therein, a horizontal pipe 42, elbow 43, elbow 44 horizontally rotatable therein, horizontal pipes 45 and 46 and a horizontally rotatable elbow 47, which is connected by pipe 48 to the main feed supply 49.

80 All of the pipes are preferably enclosed in larger steam pipes 50, which are supplied with steam by pipe 51. The steam jacketed pipes, including pipe 26 around inner pipe 39, serve to maintain asphalt or other viscous 85

90

liquid in a fluent condition. If for any reason the asphalt is allowed to cool in the system and the pipes become clogged, it is only necessary to melt the hardened material 5 by superheated steam in jacket 50.

Referring again to the movable feed discharge device (see Fig. 1), one end of each horizontal rod 30, 31, 32, etc., is journaled in a bearing 52 and is provided adjacent 10 said bearing with a side arm 53. This side arm is normally held in a vertical position by spring detents 54. They are provided with handles 55 by which they may be rotated to open and close the respective valves.

15 From Figs. 1 and 2, it may be seen that an operator standing at one place may actuate controls, *a*, *b*, *c*, *d*, and *e* for filling barrels A, B, C, D, and E. I contemplate means for simultaneously opening all valves 20 at the same time and for regulating or closing any particular valve without affecting the remaining valves. Any conventional valve control means may be used for this purpose as will be evident to those skilled 25 in the art.

Shaft 56 is mounted in bearings 57 and 57' on supports 24 and 24'. To the outer end of this shaft is keyed a hand wheel 58 and to the inner end of this shaft is keyed a 30 pulley 59 carrying a belt 60 which drives pulleys 23 for regulating the position of the carriage and for advancing the carriage.

Each nozzle 38 is provided with intersecting vanes 61 which prevent a turbulent 35 discharge and which thereby prevent splashing and spattering.

The operation of my invention may be described as follows: Receptacles, such as barrels A, B, C, D, E, F, etc. are placed 40 in rows between the columns 10. The carriage is positioned by means of hand wheels 58 over the first row of barrels. If asphalt is being fed into barrels, steam is introduced 45 into jackets 50 and into large pipe 26 for maintaining said asphalt in a fluent condition. With the nozzles properly located, controls *a*, *b*, *c*, *d*, and *e*, are rotated to open valves 38 *a*, *b*, *c*, *d*, and *e* and as soon as the barrels A, B, C, D, and E are filled, the 50 controls are closed and the carriage is moved to the next rows of barrels. The flexible feed system allows the movement of the carrier in either direction and the whole operation is thereby rendered extremely simple 55 and efficient.

While I have described the preferred embodiment of my invention, it is understood that I do not limit myself to the details set forth except as defined by the following 60 claim.

I claim:

In apparatus for filling receptacles with a normally viscous liquid, a feed pipe, a plurality of discharge pipes connected to said 65 feed pipe, valves in said discharge pipes, a

movable carriage for supporting said feed pipe, a plurality of pipe sections having rotatable connections therebetween, said pipe sections being connected between said feed pipe and a supply of viscous liquid, 70 steam jackets surrounding all of said pipes, means for moving said carriage, means adjacent said last named means for regulating said valves and connections between said valves and said regulating means. 75

Signed this 22nd day of March, 1930 at Whiting, in the county of Cook, and State of Indiana.

CLAUDE P. McNEIL.
